(57) **CLAIM**

The ornamental design for a pet bed, as shown and described.

DESCRIPTION

FIG. 1 is a front perspective view of a pet bed;

FIG. 2 is another front perspective view thereof;

FIG. 3 is a rear perspective view thereof;

FIG. 4 is another rear perspective view thereof;

FIG. 5 is a top plan view thereof;

FIG. 6 is a front view thereof;

FIG. 7 is a rear view thereof;

FIG. 8 is a left-side view thereof;

FIG. 9 is a right-side view thereof;

FIG. 10 is a front perspective view of a second embodiment thereof;

FIG. 11 is another front perspective view of FIG. 10;

FIG. 12 is a rear perspective view of FIG. 10;

FIG. 13 is another rear perspective view of FIG. 10;

FIG. 14 is a top plan view of FIG. 10;

FIG. 15 is a front view of FIG. 10;

FIG. 16 is a rear view of FIG. 10;

FIG. 17 is a left-side view of FIG. 10;

FIG. 18 is a right-side view of FIG. 10;

FIG. 19 is a front perspective view of a third embodiment thereof;

FIG. 20 is another front perspective view of FIG. 19;

FIG. 21 is a rear perspective view of FIG. 19;

FIG. 22 is another rear perspective view of FIG. 19;

FIG. 23 is a top plan view of FIG. 19;

FIG. 24 is a front view of FIG. 19;

FIG. 25 is a rear view of FIG. 19;

FIG. 26 is a left-side view of FIG. 19;

FIG. 27 is a right-side view of FIG. 19;

FIG. 28 is a front perspective view of a fourth embodiment thereof;

FIG. 29 is another front perspective view of FIG. 28;

FIG. 30 is a rear perspective view of FIG. 28;

FIG. 31 is another rear perspective view of FIG. 28;

FIG. 32 is a top plan view of FIG. 28;

FIG. 33 is a front view of FIG. 28;

FIG. 34 is a rear view of FIG. 28;

FIG. 35 is a left-side view of FIG. 28; and,

FIG. 36 is a right-side view of FIG. 28.

The broken lines are included for the purpose of illustrating unclaimed subject matter only and form no part of the claimed design.
